UNITED STATES PATENT OFFICE.

GEORGE C. HESTER, OF CHICAGO, ILLINOIS.

STORE-FRONT CONSTRUCTION.

1,193,144.

Specification of Letters Patent.

Patented Aug. 1, 1916.

Application filed February 4, 1914. Serial No. 816,580.

To all whom it may concern:

Be it known that I, GEORGE C. HESTER, of Chicago, in the county of Cook, and in the State of Illinois, have invented a certain new and useful Improvement in Store-Front Construction, and do hereby declare that the following is a full, clear, and exact description thereof.

My invention relates to the supporting frame work or sash for large plates or panes of glass used in store front construction and particularly to that type in which the frame work or sash is made of sheet metal, such as sheet copper.

The object of my invention is to improve the sash so that structurally it will be rigid or stiff in parts which are obliged to bear pressure falling upon them from the glass from wind pressure and other causes and which will have important functions in other respects, and which withal will be economical in its use of sheet metal and cheaper to manufacture, and to this end my invention consists in the construction substantially as hereinafter specified and claimed.

Referring to the accompanying drawings—Figure 1 is a perspective view of a portion of a store front embodying my invention; Fig. 2 is a detail view in perspective of a portion of the member which carries the inner glass engaging element of the structure; Fig. 3 a similar view of the same part showing a different embodiment of my invention; Fig. 4 is a similar view of still another embodiment of my invention; Fig. 5 is a cross section of a store front sash of yet another construction embodying my invention; Fig. 6 a detail view in perspective of a form of setting block that may be used.

Briefly described, the type of sash to which my invention relates comprises a glass engaging clamp formed by an inner member of sheet metal that has a bearing face for the inner side of the glass and an outer member of sheet metal which by means of screws is drawn or forced against the outer side of the glass with the desired degree of binding or clamping pressure. The inner clamping member has a gutter-forming portion to receive water of condensation running down the inner side of the glass and wash water, and openings are provided leading from said gutter downward through which the water is discharged and it eventually finds its way to the outside of the window through suitable openings provided in the sash for that pur-

pose. The openings provided for the discharge of water also are useful as air passages to allow a circulation of air for ventilation.

In the embodiment of my invention shown in the drawing, the inner gutter-carrying and glass engaging member is formed of sheet metal, preferably copper, that in cross section is L-shaped, comprising a vertical part 10 and a horizontal part 11, that, of course, are integral and this L-shape conforms to the formation at the front of the window provided by the sill and floor 12, the horizontal part 11 resting upon the top of the sill and the vertical part 10 bearing against the shoulder or rabbet formed in the sill and by the front edge of the flooring.

The vertical part 10 by embossing its upper portion is bent outward to form a series of glass-engaging bosses 13 having extended vertical surfaces that bear against the glass and from which the strip extends preferably inward and upward at a slight incline and then at its upper edge is bent downward, these bosses being separated at intervals by inwardly extending depressions that form vertical openings 14 next to the inner face of the glass through which water running to the gutter 15 formed by the inclined upper portion of the strip may pass downward to the horizontal part 11. Toward its forward edge the horizontal part 11 is raised by an embossing operation to provide a series of separated bosses or projections 16 which are separated by depressions that form horizontal openings 17 through which water passing from the gutter on the inside of the glass may finally be discharged to the outside of the window.

The sheet or pane of glass 18 is held against the inner bosses 13 by a rail 19 made of sheet metal, which in cross section is symmetrical in form and at one edge has a lip or vertical flange that bears against the outer side of the glass and at the opposite edge has a horizontal upper flange that rests on the top of the bosses, screws 20 being provided at intervals which pass from the outside through said outer clamp member.

At intervals apart, but fairly close together, I form in the vertical part 10 beneath the bosses 13 thereon by an embossing operation vertical ribs or corrugations 21 which project outward and similar ribs or corrugations in the horizontal part 12 which project upward, the vertical ribs extending

to the angle or corner formed by the vertical and horizontal parts 10 and 11. The ribs in the horizontal part 12 may extend only partially from the corner toward the bosses 5 or projections 16 in which case, as clearly shown in Figs. 2 and 4, they are tapering in form, these ribs being designated 22, or, also as shown in Figs. 2 and 3, they may extend from the corner entirely out to the 10 bosses or projections 16 their upper surfaces being horizontal, and this form is designated 220. When the ribs have the form designated 22 they may be placed as frequently as desired between the horizontal 15 openings 17, for since they terminate before reaching the projections or bosses 16 they offer no obstacle to the ready flow of water through the openings 17. These vertical and horizontal bosses obviously impart 20 part such stiffness or rigidity to the sheet metal as to cause it to resist bending at the corner formed by the vertical gutter carrying part 10 and the horizontal part 11, the rigidity or stiffness thus imparted being 25 sufficient to withstand the inward pressure from the glass under the conditions of actual use. Experience has shown that a stiff unyielding support at the inner side of the glass, such as my structure provides, is de- 30 sirable and by my construction this is provided because the inner gutter is rigid and unyieldable so that it cannot yield under pressure to which it may be subjected directly by the glass and bending at the corner 35 is prevented by the stiffening beads or ribs. Bending or yielding is objectionable because the sheet metal that is used is deficient in elasticity so that it is possible for the parts to be subjected to pressures from 40 the glass by heavy winds or otherwise which will result in such displacement of the sheet metal member that when the pressure is removed from the glass the sheet metal will not return to its former position but will 45 take a "set" that results in a loose setting for the glass.

The horizontal ribs or corrugations besides their importance as stiffening means, are also valuable in the form designated 220 50 in that should the wood or leather setting upon which the bottom edge of the glass rests be displaced or removed with the result that the heavy pane of glass would settle its descent would be limited by the contact of its bottom with said horizontal ribs, and hence, the dropping of the glass to an extent which would result in the production 55 of a space between the top edge of the glass and the setting above it is prevented. It is 60 desirable and necessary in setting the glass to support its bottom edge above the bottom of the sash so as to provide the necessary space for the passage of water and for ventilation and small pieces of leather and wood 65 are commonly used for that purpose. Wood

rots and thus the glass is deprived of its support and settles and both the wooden settings and the leather settings may be displaced accidentally. By the use of the horizontal ribs 220 thin wooden or leather setting blocks may be placed upon the ribs and if the wood rots or the wooden or the leather settings are displaced, the glass can descend only to the tops of the ribs, thus preserving a clear space beneath the glass and also 70 limiting the descent so that no opening is formed at the top of the glass. Dust finding its way into the spaces beneath the glass is localized or trapped by the horizontal ribs instead of collecting at one point in a quantity which might result in choking the water and air passages. Dust collected in small 75 quantities in several places by reason of the presence of the ribs, can be more readily flushed or washed out, and, indeed, will be 80 automatically washed out by the action of wash water and water of condensation.

The horizontal ribs or bosses, and especially those near the ends of the sash bar perform the further important function of 85 preventing water finding its way to the corner joints or miters at the ends of the sash and passing therethrough and into the wood-work beneath and rotting the woodwork.

Another benefit from limiting the settling 90 of the glass from the rotting or displacement of the wood or leather settings is that the bottom edge of the glass is prevented from falling into contact with the clamping screws or their nuts so that the removal of 100 the screws is not interfered with as would be the case with the weight of the glass after settling resting upon the screws or nuts; and if in settling the edge of the glass falls upon the exposed edge of the screw, such 105 thread in the unscrewing operation tends to break or fracture the glass by the thread cutting therein.

As shown in Fig. 3, the ribs 220, may be arranged in pairs close together and between a pair a hole 221 is provided for the passage of the clamping screws which hold the members of the sash together upon the glass and for the passage of screws or nails for fastening the horizontal member to the 110 wooden portion of the sill, the clamping screws and the attaching screws or nails alternating with each other. A hole 221 being situated between the bosses or projections 220 will prevent water reaching the 115 holes and finding its way therethrough to the wood where it will be apt to rot it. A pair of ribs 220 between which a hole is provided will, of course, be situated away from the vertical openings 14 for leading water 120 from the gutter. Instead of a pair of ribs close together, as shown in Fig. 3, a single comparatively wide rib with a preferably flattened top may be employed and provided with a screw hole 221 for the passage 125

of a screw, with the same advantage as to the exclusion of water from the hole, as the pair of ribs 220 affords.

Instead of providing the bosses, or projections 13 by an embossing operation, they may, as shown in Fig. 4, be provided by the use of a strip 23 of lead or other material which at intervals is provided with vertical notches 24 which form water and air passages and whose upper side is inclined downwardly and outwardly toward the face of the glass in order to provide the gutter. This strip may be attached to the vertical member 10 in any desired way. A convenient way is that illustrated in Fig. 4, which consists of tongues 25 struck out from the vertical member 10 which form hook-like projections that reach into the notches 24 so as to be out of the way of the glass and thereby support the strip 23. The tongues 25 may be pinched to clamp or bind the strip 23. If desired, the vertical member 10 may at its top at the plane of the top of the strip 23, be carried horizontally inward and then upward to extend the area of the gutter. The vertical stiffening ribs or corrugations 26 shown in Fig. 4, reach from the underside of the strip 23 to the horizontal member 11.

The glass-engaging faces of the sash members may be flat, as shown in Figs. 1, 2 and 3, or as shown in Figs. 4 and 5 they may be rounded so as to form a fulcrum to permit the slight rocking of the glass which takes place under wind pressures and thus allows the bottom edge of the glass to partake of the vibratory movement which is thus produced and thereby eliminates the danger of breakage of the bottom edge of the glass which would exist were it fixedly supported. A convenient form of setting block 27 for this arrangement is shown in Figs. 5 and 6. Said block has in its upper side a channel 28 into which the bottom edge of the glass projects and said block, while being thus attached to the glass so as to move with it, rests upon the horizontal part 11 of the sash member so as to slide back and forth thereover. The setting block 27 has its under surface provided with separated bearing points 29 to reduce the extent of contact thereof with the sash so as to facilitate the moving of the setting block with the glass, but enough friction is desirable to prevent too free movement of the glass. The dotted lines in Fig. 5 show to an exaggerated degree the movement of the

glass under wind pressure when it rocks between the round or convex bearing surfaces which the sash provides.

The ribs or corrugations may be either round or flat or any desirable form in cross section which will be consistent with the purpose for which I provide them and as will be evident they are not dependent for their use and value upon the particular form of the sash in other respects.

Having thus described my invention what I claim is—

1. A sash for store front construction comprising a glass-engaging clamping member of sheet metal having integral ribs or projections on the side toward the glass, said member having an upper offset glass-engaging portion from which said ribs extend downward.

2. A sash for store front construction comprising a sheet metal member having a vertical part at one side of the glass and a horizontal part beneath the glass, the horizontal part having upwardly extending integral ribs or projections that reach to the corner formed by the vertical and horizontal parts.

3. A sash for store front construction comprising a sheet metal member having a vertical part at one side of the glass, and a horizontal part beneath the glass, the horizontal part having upwardly extending ribs or projections, and the vertical part having outwardly extending ribs or projections, the ribs or projections in both cases reaching to the corner formed by the vertical and horizontal parts.

4. A sash for store front construction comprising a sheet metal member having a vertical part at one side of the glass with separated glass-engaging projections the spaces between the latter forming water passages and having a horizontal part beneath the glass with separated projections, the spaces between the projections forming water passages, and said horizontal part also having stiffening ribs which extend part way from the vertical part to the separated projections on the horizontal part.

In testimony that I claim the foregoing I have hereunto set my hand.

GEORGE C. HESTER.
